[57] CLAIM

The ornamental design for a grippable container dome, as shown and described.

DESCRIPTION

FIG. 1 is a front elevational view of a grippable container dome embodying my new design;

FIG. 2 is a right side elevational view of the grippable container dome of FIG. 1, the left side elevational view being identical;

FIG. 3 is a top plan view of the grippable container dome of FIG. 1; and,

FIG. 4 is a bottom plan view of the grippable container dome of FIG. 1.

The broken line showing in FIGS. 1-3 of the container finish and sidewall is for illustrative purposes only and forms no part of the claimed design.
